UNITED STATES PATENT OFFICE

CLARENCE L. JOHNSTON, OF OAKLAND, CALIFORNIA, ASSIGNOR TO AMERICAN SALES BOOK COMPANY, LIMITED, OF TORONTO, ONTARIO, CANADA, A CORPORATION OF ONTARIO, CANADA

SELECTING REGISTER

Application filed February 2, 1925. Serial No. 6,174.

This invention relates to autographic registers and with regard to its more specific features to devices intended to make a plurality of copies of a record and to retain 5 one or more of said record copies within a locked compartment in the form of a continuous zigzag pad.

An object of this invention is to provide a device of the character described which will 10 insure the proper folding of the record pad and the proper coordination between the folding and the feeding mechanism relative to the locked compartment.

A further object is to provide a device of 15 the character described which will be simple of construction and more efficient in operation.

Other objects of the invention will in part 20 be obvious and will in part appear herein- after.

It has heretofore been proposed to provide autographic registers with a compartment for the reception of a supply pad comprising a plurality of strips interfolded zigzag into a 25 flat package and to feed these strips over a tablet and to divert one or more of them into a record compartment where it is intended that they should be refolded to assume the original flat form. Difficulty has been ex- 30 perienced however, due to the tendency of the strips to continue to feed forward from the feeding mechanism and to accumulate in the locked compartment in a confused or un- 35 folded mass which may become of sufficient bulk to interfere with the feeding mechanism and in any event interfere with the usefulness and accessibility of the permanent record.

It has also heretofore been proposed posi- 40 tively to grip certain of the sheets to bring them into their folded position by engaging specially prepared apertures in the sheets.

In accordance with the present invention, 45 means are provided for positively directing the sheets to their position.

The invention accordingly comprises the 50 features of construction, combinations of elements, and arrangement of parts, which will be exemplified in the constructions herein- after set forth and the scope of the applica-

tion of which will be indicated in the claims.

For a fuller understanding of the nature and objects of the invention reference should be had to the following detailed description taken in connection with the accompanying 65 drawings, in which:

Figure 1 is a longitudinal section of the machine, the strip being illustrated in dotted lines and part of the mechanism being broken away,

Fig. 2 is a detail of the folding mechanism showing the relation of the strip to the folding finger at the moment the cam for operating the folding arm comes into engagement,

Fig. 3 is a similar view showing the relation 65 of the folding arm to the strip when the arm is in depressed condition,

Fig. 4 is a similar view showing the relation of the folding arm to the strip when the strip is released to permit the continued feed- 70 ing of the next form,

Fig. 5 is a cross-section through the machine on the line 5—5 of Fig. 3, and

Fig. 6 is a fragmental view showing the relation of the arm, operating cam and finger. 75

The numeral 1 indicates a casing divided by partitions 2 into a supply compartment A and a record compartment B. The supply compartment A preferably has a pivoted end wall 3 to facilitate insertion of a zigzag flat 80 pad 4 composed of a plurality of strips of record leaves interfolded zigzag to form superposed sets of superposed record leaves, and these record leaves may be provided with control apertures bearing definite relation to the 85 forms thereon. Arranged above the compartment A is a tablet 5 and the strips from the pad 4 are carried over separators 6, 7 and 7' into superposed relation on the tablet 5. The separators 7 may be hollow cylinders 90 adapted to receive rolls of manifolding paper and they may be provided with slots 8 to permit the manifolding paper to be carried out and interleaved between the strips.

Feeding means are provided which in the broad aspect of the invention may be of any suitable character. In the form illustrated, it comprises disks 9 mounted on a shaft 10 journaled in the casing, the disk being of 100

slightly greater circumferential length than a single record form.

A roll 11 is journaled in a cross bar 12 pivoted at one side of the frame and the pivots of this roll are urged downwardly by springs 13 in the customary manner so that when the cross bar 12 is in place the strips will be firmly gripped between the disks 9 and the roll. It will be understood that these disks will be in line with the control apertures in the record sheets. The shaft 10 is rotated by a handle 14 and a depressible stop 15 is arranged to limit the feed at the conclusion of the feeding of the form. Simple auxiliary starting means to engage the webs at the sides of the control apertures may be arranged to start the feeding of the webs as soon as the handle 14 passes the stop 15.

The record compartment B is arranged relative to the feeding mechanism so that as a strip is fed into it from the feeding means, the normal stiffness of the paper tends to carry the strip toward the far end of the compartment. Since however it is desired to fold the strip zigzag, a fold arm 16 is mounted upon the shaft 17 journaled in the sides of the casing adjacent to the path of the strip. This folding arm is arranged alternately to direct the strip toward the far end and toward the near end of the record compartment and is so timed relative to the feeding means that alternate fold lines are directed to opposite ends. A cam 18 mounted on a stub shaft 19 attached to one wall of the casing is operated from the shaft 10 by gears 20 and 21. The gear 20 is of twice the size of the gear 21 so that the cam 18 is rotated once for every two revolutions of the shaft 10. A lug 22 on the cam 18 is arranged in the pathway of a finger 23 upon the shaft 17 and these parts are so proportioned that as the cam rotates to bring the lug into engagement with the finger, the arm 16 is depressed downwardly to an extent sufficient to engage the paper and definitely fold it toward the near end of the compartment. A spring 24 attached to the casing at one end retains the arm 16 normally raised unless depressed by the cam 22.

The cam 22 is so timed relative to the feeding mechanism as illustrated in Figs. 2, 3 and 4, that the fold line between two adjacent sheets is substantially opposite the tip of the folding arm as the latter is operated so that the folding of the paper is definitely effected at the fold line.

The folding arm has a generally curved form so that when in its depressed position as illustrated in Fig. 3, it serves as a deflector or guide to deflect the strip toward the near end of the record compartment, whereas when the arm is in its raised position, it serves to bear upon the upper side of the strip if the latter should rise too high and direct it toward the far end of the compartment. The lug 22 is of such shape as to hold

the arm depressed until the fold line has substantially reached its position, allowance being made for the thickness of the full pad. Thereupon it is immediately released.

The operation of the device is as follows: 70

The record pad having been inserted in the compartment A and fed through the machine in the usual manner, one of the strips is carried downwardly beneath the arm 16 and the others carried out of the machine. Assuming the machine to be in the position shown in Figure 1 at this moment, and a record having been made upon the sheets superposed upon the tablet 5, the stop 15 is depressed and 75 the handle 14 turned one revolution. 80

At the commencement of this feeding movement, when the strip has been fed about one-fourth of its length, the lug 22 comes into engagement with the finger 23 to depress the arm 16. This depression however, requires an appreciable length of time during which a further feeding of the strip takes place until the position shown in Fig. 3 is reached. After this, because of the circumferential length of the lug 22, the arm is 90 maintained depressed for a short time. While the strip is further fed and guided into position by the arm, the adjacent fold of the strip is close to its final position, whereupon, as illustrated in Fig. 4, the arm snaps 95 back. The lug 22 is arranged to release the arm at this time because the continued feeding of the strip causes it to bow outwardly and the presence of the depressed arm at that time would interfere with this operation and cause the buckling of the sheet. Because of the circumferential length of the lug 22 and of the cam 18, it will be observed that the strip directing and folding member or arm 16 is caused to dwell for a period 100 in each of its alternate positions in which it is shown respectively in Figs. 3 and 4. In the lower of these positions as shown in Fig. 3, the strip is fed by the feeding mechanism against the folding member or arm 16 which thus acts as a guide to direct the feeding strip into folded position at the near end of the zigzag folded pad. Also, when the arm 16 is in the act of moving downwardly, it will 105 engage the adjacent face of the record strip and positively move the latter toward folded position. 110

The bowing referred to continues during the completion of the feeding of this sheet and during the feeding of the next record sheet. During this portion of the feed, the sheet may tend to curve upwardly due to its own stiffness and if this curving occurs, the arm 16 will guide it downwardly toward its position. As soon, however, as the next weakened line reaches the outer edge of the bow, the strip tends to fold sharply and drop into its proper place upon the paper pad due to the feeding impulse, to the weight of the paper and the weakness of the strip at the 115 120 125 130

fold. It is substantially at this time that the folding arm is in position again to be moved down into engagement with the other record sheet.

As stated above, the feed mechanism is adapted to grip the strips and to feed them forwardly, the feed disks 9 being aligned with feed control apertures in the strips positioned in definite relation with reference to the blank forms and necessarily also with reference to the folds of the strips. When these feed control apertures come into alignment with the feed grip, the strip feed will be checked even though the feed disks continue to advance. This action adjusts the relative position of the strips with reference to the strip positioning guide or arm 16 which is also controlled and operated by the feeding mechanism. By virtue of this action, the transverse fold lines of the lower or storage record strip are longitudinally adjusted or timed with reference to the actuation or positioning of the strip guide 16. Thus, certain definite portions along the length of the record strip in the vicinity of the transverse fold lines are projected by actuation of the feeding mechanism against the strip guide and folding member 16, thereby guiding the strip into folded condition when the guide 16 is in the position shown in Fig. 3. Similar actuation may also occur when the fold member 16 occupies the position shown in Figs. 1 and 2. Thus, the strip is adjusted longitudinally with reference to the folding positions of the member 16 even though there may be slippage or other inaccuracies of the feeding mechanism in feeding the strips. This feature of the improved mechanism maintains the correct relative positioning of the strip and folding member 16 for the most satisfactory accomplishment of the folding function. Any tendency to failure in the folding function is thus greatly diminished over preexisting devices for similar purposes.

It will be understood that the record strip or strips will be started after each aligning operation brought about by engagement of the strip apertures in the grip of the feed disks. Such starting may be accomplished by hand, if desired, by pulling upon the forward ends of the strips or otherwise, but preferably some preferred mechanism will be employed such as an auxiliary starter as above referred to, a form of which is disclosed in the Johnston patent for autographic register #1,658,127, issued February 7, 1928.

It will be seen that every alternate fold line will be automatically deflected to the near end of the record compartment by the deflecting arm 16; whereas each other fold line will be carried to its place at the far end of the compartment by the bowing action referred to.

If there is a decided bias on the part of

the sheets making it desirable to refold them in the same direction that they were originally folded, it will be desirable to properly time the cam 22 relative to the strip, but it has been found feasible to make a pad of the character described which will fold with equal facility in either direction. With such feed, it is unimportant how the machine be timed since it is immaterial whether the strip be refolded in its original form or in the reverse form.

Since certain changes may be made in the above construction and different embodiments of the invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent, is:—

1. In a device of the character described, in combination, means to feed a record strip into inscription-receiving position, a record strip storage compartment adjacent said feeding means, a shiftable strip guide positioned adjacent the path of movement of the feeding strip and adjacent said storage compartment, and a mount mounting said strip guide so that it may be shifted into alternate strip-guiding positions, in one of which the strip may be fed thereagainst by the feeding means thereby to guide and deflect the strip into folded condition at one end of the folded pad in said compartment and in the other of the alternate positions, said strip may be fed by the feeding means against said strip guide, thereby to guide and deflect the strip into folded condition at the other end of said pad, and positively operated mechanism to move said strip guide in definite predetermined cycles toward and away from its alternate strip guiding positions.

2. In a device of the character described, in combination, means to feed a record strip into inscription-receiving position, a record strip storage compartment adjacent said feeding means, a shiftable strip guide positioned adjacent the path of movement of the feeding strip and adjacent said storage compartment, and a mount mounting said strip guide for shifting into alternate strip-guiding positions, in one of which the strip may be fed thereagainst by the feeding means thereby to guide and deflect the strip into folded condition at one end of the folded pad in said compartment and in the other of the alternate positions, said strip may be fed by the feeding means against said strip guide, thereby to guide and deflect the strip into folded condition at the other end of said pad, and means connected for operation by said feeding means to shift said strip guide into

either alternate strip-guiding position in timed sequence with strip feed.

3. In a device of the character described, in combination, means to feed a record strip into inscription-receiving position, a record strip storage compartment adjacent said feeding means, a strip-guiding and folding finger pivotally mounted adjacent the path of movement of the feeding strip and adjacent said storage compartment, the pivotal point of said folding finger being positioned adjacent to and above the path of movement of said feeding strip as it emerges from said feeding means so as to swing downwardly toward the feeding means into strip cooperative position thereby to guide and deflect the feeding strip into folded condition in said compartment, means for moving said folding finger downwardly on its pivotal mounting into strip cooperative folding position, means to cause said finger to dwell for a period whereat the strip may be fed thereagainst by the feeding means, and means for swinging said finger upwardly away from the feeding means.

4. In a device of the character described, in combination, means to feed a record strip into inscription-receiving position, a record strip storage compartment adjacent said feeding means, a strip-guiding and folding finger pivotally mounted adjacent the path of movement of the feeding strip and adjacent said storage compartment and adapted to swing downwardly toward the feeding means into strip cooperative position so that the strip may be fed thereagainst by the feeding means, thereby to guide and deflect the strip into folded condition in said compartment, said supporting finger being swingable upwardly away from the feeding means, an operating lug operatively connected to said finger, a cam cooperating with said lug to move said finger into strip-guiding position and to hold it there during strip feeding action of the said feeding means and driving connections between said feeding means and said cam to shift said finger into strip-cooperating position in timed sequence with strip feed.

5. In a device of the character described, in combination, means to feed a record strip into inscription receiving position, a record strip storage compartment adjacent said feeding means, a shiftable strip guide mounted adjacent the path of movement of the feeding strip and adjacent said storage compartment, means for shifting said strip guide out of the path of normal strip feed whereby the strip may then be projected by the feeding means to one end of a folded pad, and means for shifting said strip guide downwardly into the path of strip feed wherein the strip is fed thereagainst by said feeding means thus to guide and deflect the strip to the other end of said pad.

6. In a device of the character described, in combination, means to feed a record strip into inscription receiving position, a record strip storage compartment adjacent said feeding means, a shiftable strip guide mounted adjacent the path of movement of the feeding strip and adjacent said storage compartment, means to shift said strip guide to position it and to cause it to dwell for a period at one side of the path of normal strip feed out of normal contact with the strip while the latter is being fed to one part of a folded pad, and means to shift said strip guide to position it and to cause it to dwell for a period adjacent the path of normal strip feed in position to contact with the strip and to guide and position it while being fed to another part of the folded pad.

7. In a device of the character described, in combination, means to feed a record strip into inscription receiving position, a record strip storage compartment adjacent said feeding means, a shiftable strip guide mounted adjacent the path of movement of the feeding strip and adjacent said storage compartment, means to shift said strip guide to cause it to engage with and deflect the strip toward folded position, and means to cause said strip guide to dwell for a period adjacent the path of normal strip feed in position to contact with the feeding strip and to guide and position it into folded position during said dwell.

8. In a device of the character described, in combination, means to feed a record strip into inscription receiving position, a record strip storage compartment adjacent said feeding means, a shiftable strip guide mounted adjacent the path of movement of the feeding strip and adjacent said storage compartment, and means for shifting said strip guide into each of a plurality of positions relative to the path of strip feed and causing it to dwell there for a period during strip feed in each of said positions.

9. In a device of the character described, in combination, means to feed a record strip into inscription receiving position, a record strip storage compartment adjacent said feeding means, a shiftable strip guide mounted adjacent the path of movement of the feeding strip and adjacent said storage compartment, and means for shifting said strip guide relative to the path of strip feed and causing it to dwell for a period adjacent said path in position to guide the strip into folded position during strip feed.

10. In a device of the character described, in combination, means to feed a record strip into inscription receiving position, a record strip storage compartment adjacent said feeding means, a shiftable strip guide mounted adjacent the path of movement of the feeding strip and adjacent said storage compartment, means controlled by said feeding

- means for shifting said strip guide relatively to the path of strip feed at predetermined intervals into position wherein the strip may be fed thereagainst by said feeding means 5 thus to guide and deflect the strip into folded condition, and means embodied in said feed means to adjust the relative strip advancement with reference to the operative folding position of said shiftable strip guide thus to cause predetermined parts of the strip to be fed by the feed means against said strip guide thus to facilitate the folding operation. 11. In a device of the character described, in combination, means to feed a record strip 15 into inscription receiving position, a record strip storage compartment adjacent said feeding means, a shiftable strip guide mounted adjacent the path of movement of the feeding strip and adjacent said storage compartment, means controlled by said feeding means for shifting said strip guide relatively to the path of strip feed at predetermined intervals into position wherein the strip may be fed thereagainst by said feeding means thus to 20 guide and deflect the strip into folded condition, means embodied in said feed means to adjust the relative strip advancement with reference to the operative folding position of said shiftable strip guide thus to cause predetermined parts of the strip to be fed by the feed means against said strip guide thus to facilitate the folding operation and means whereby said guide shifting means causes said guide to dwell in its strip guiding position while the strip is being fed thereagainst and guided thereby into folded position. 12. In a device of the character described, in combination, feeding means to feed into inscription receiving position a record strip 40 having successive record sheets and longitudinally aligned feed control apertures having definite relation, respectively, with said record sheets, a record strip storage compartment adjacent said feeding means, a shiftable strip guide mounted separately from said feeding means adjacent the path of movement of the feeding strip and adjacent the storage compartment, said strip guide being shiftably mounted for movement into position relatively to the feeding means and strip path so that the strip may be fed thereagainst by the feeding means and thereby guided and diverted into folded condition in said compartment, and operating connections for said strip guide operatively connected to said feeding means for controlling the strip guiding position of said guide, said feeding means including a strip gripping feed disk adapted to grip the strip in longitudinal alignment 45 with the feed controlling apertures so as to release feeding grip on the strip when said apertures come into alignment with the feeding strip, thereby to check strip feed during continued operation of said feeding means 50 and of said strip guide operating connections 55 thus to adjust the operating position of the latter relatively to said checking of the strip feed. 13. In a device of the character described, in combination, feeding means to feed into inscription receiving position a record strip having successive record sheets and longitudinally aligned feed control apertures having definite relation, respectively, with said record sheets, a record strip storage compartment adjacent said feeding means, a shiftable strip guide mounted adjacent said feeding means in the strip path for movement into contact with the face of the strip in its path to said compartment so as to divert the strip into folded condition within said compartment, an operating lug operatively connected to said strip guide, a cam cooperating with said lug to move said guide into strip cooperative position and operating connections between said feeding means and said cam to control the strip diverting position of said guide, said feeding means including a strip gripping feed disk adapted to grip the strip in longitudinal alignment with the feed control apertures so as to release feeding grip on the strip when said apertures come into alignment with the feeding strip, thereby to check strip feed during continued operation of said feeding means and of said strip guide operating connections thus to adjust the operating position of the latter relatively to said checking of the strip feed. 90 In testimony whereof I affix my signature. CLARENCE L. JOHNSTON. 95 100 105 110 115 120 125 130
